UNITED STATES PATENT OFFICE.

CLARENCE HARRY FORNEY, OF JERSEY CITY, NEW JERSEY, ASSIGNOR TO FORNEY FIBRE COMPANY, OF JERSEY CITY, NEW JERSEY, A CORPORATION OF NEW JERSEY.

CLOTH BOARD.

Application filed August 19, 1927. Serial No. 214,163.

This invention relates to cloth boards upon which bolts of fabric may be wound, and more particularly to the type which is of built-up or framed construction designed 5 to avoid the weight of a solid board.

In the framed cloth boards heretofore used, the struts have been merely butted between the side members, or secured in such a manner that they may twist or move laterally, which greatly reduces the rigidity of 10 the board. In some types developed for various reasons the end struts are of different shape or construction from the intermediate struts, which renders the construction 15 as well as assembly an expensive process.

It is therefore a general object of the invention to simplify and improve the construction of cloth boards of this character. 20 It is a specific object of the invention to prevent twisting or lateral displacement of the strut member, so as to improve the rigidity of the board.

Other objects and features of novelty will 25 be apparent from the following description and the accompanying drawings, in which

Fig. 1 is a plan view partly in section of my improved cloth board;

Fig. 2 is an end elevation of the structure 30 shown in Fig. 1; and

Fig. 3 is a cross-section taken along the line 3—3 of Fig. 1.

Referring more particularly to the drawings, the embodiment of my invention shown 35 therein comprises a pair of hollow side members 10, and a plurality of strut members 11 arranged perpendicularly thereto. The member 10 is preferably cylindrical, and may be formed of a pasteboard tube. A 40 series of rectangular slots 12 are formed by cutting substantially half way through the tube at spaced intervals. The ends are similarly cut away forming notches 13, having their outer sides open.

The strut members 11 may be formed of 45 any light material, preferably wood. Each side of each end of the strut 11 is notched as at 14, forming a shoulder of a depth equal to the thickness of the wall 15 of the tube 10. The central portion of the end 50 of the strut is shaped to fit the hollow interior of the tube 10, and in the embodiment of the invention shown comprises a semi-circular portion 16.

When the side members 10 and the struts

11 have been constructed as described above, they may be assembled by merely fitting the ends of the struts in the notches or slots of the side member 10, and secured in place by gluing or other suitable fastening means. 60

It should be noted that each of the strut members 11 is identical. This permits very rapid assembly, as the mechanic is not required to select a different strut member for the end notches and the intermediate slots. 65 Furthermore, the slot 12 and the notch 13 may be constructed with the same tool, the only difference being that the cut end of the tube removes the outer side of the notch 13.

Another advantage lies in the fact that 70 the strut 11 passes through the notch 12 and the end portion 16 fits snugly against the hollow interior of the tube and at the same time the edge of the slot 12 fits into the notch 14 and abuts the shoulder formed 75 thereby. A very rigid construction is therefore accomplished, not only by the snug fits provided but also by the curved edge of the slot 12 abutting against the flat side of the strut 11. 80

This construction not only prevents lateral movement of the struts, but also prevents their pivoting about their end attachments. An added feature resides in the fact that the notch 14 permits the edge of the 85 strut 11 to be flush with the outer surface of the tube 10 so that there is no projecting end, and a smooth exterior surface is provided.

While the invention has been shown and described in great detail for one embodiment 90 of the broad idea, it is not limited to the details shown but includes such modifications as come within the scope of the appended claim.

Having thus described the invention what 95 is claimed as new and desired to be secured by Letters Patent is:

A cloth winding form constituting a frame upon which bolts of cloth may be wound comprising in combination, a pair of 100 cylindrical pasteboard tubes forming the side members of said frame, and a plurality of rectangular wooden struts arranged perpendicular thereto between said tubes to form the end members and intermediate 105 members of said frame, each of said tubes being cut substantially half way through their adjacent sides at the ends and at spaced intervals by aligned rectangular slots to receive the ends of said struts, the ends of 110

said struts being notched at each side forming shoulders of a depth to receive the straight edges of said slots, and the central portions of the ends between said shoulders being rounded to snugly fit the inner surface of said pasteboard tube, whereby when the ends of the struts are inserted in the slots, the sides thereof may be snugly received between the shoulders formed by the

sides of said slots and prevent lateral displacement of the struts, each of said struts being identical, whereby any strut may be placed in any aligned pair of slots during assembly. 10

In testimony whereof I hereunto affix my 15 signature.

CLARENCE HARRY FORNEY.
